No. 761,133.

PATENTED MAY 31, 1904.

H. P. BALL.
ELECTRIC SWITCH.

APPLICATION FILED SEPT. 30, 1902.

NO MODEL.

UNITED STATES PATENT OFFICE.

HENRY PRICE BALL, OF NEW YORK, N. Y., ASSIGNOR TO THE GENERAL INCANDESCENT ARC LIGHT COMPANY, OF NEW YORK, A CORPORATION.

ELECTRIC SWITCH.

SPECIFICATION forming part of Letters Patent No. 761,133, dated May 31, 1904.

Application filed September 30, 1902. Serial No. 125,434. (No model.)

To all whom it may concern:

Be it known that I, HENRY PRICE BALL, a citizen of the United States, residing at New York, county of New York, State of New York, 5 have invented certain new and useful Improvements in Electric Switches, of which the following is a specification.

My invention relates to oil-switches; and it consists in the construction of the switch and 10 the mechanism employed for operating the switch and also to the support for the oil-well of the switch.

The object of my invention is to simplify 15 the construction of such switches and to provide a convenient and simple means for supporting the oil-well of the switch on the back of the switchboard.

The accompanying drawings will serve to 20 illustrate my invention, in which—

Figures 1 and 2 are side elevations of the 25 switch mechanism, also showing vertical sections through the switchboard, supporting-plate, and oil-well. These views, respectively, show the switch in the closed and open positions and illustrate different forms of support 30 for the oil-well. Fig. 3 is a view of the actuating mechanism looking from the right of Figs. 1 or 2. Fig. 4 is an enlarged detail of a portion of the support for the oil-well shown in Fig. 1.

Similar letters and numerals indicate like 35 parts throughout the several figures.

In the drawings, A indicates a switchboard. Mounted on the back of the switchboard is a 40 bracket B. This bracket may be constructed as shown in Fig. 1 or as shown in Fig. 2. Mounted in the bracket B is a support C for the oil-well D. In Fig. 1 the support C is shown as attached to and forming a part of the oil-well D. This support has two arms E F. The arm E is carried backward and then upward as a pin portion G, which is introduced in a shaped slot H in the upper arm I of the bracket B. This slot is given a peculiar shape, as shown in Fig. 4, to permit of the angular movement of the pin portion G.

The lower arm F of the support C is provided with a dovetail end J, which takes in a cor-

responding dovetail slot K in the lower arm L of the bracket B. By lifting the oil-well 50 upward until the dovetail end J leaves the dovetail part K the well may be tilted and detached from the bracket B.

It will be observed that the shaped slot H permits the angular movement of the pin 55 portion G of the support.

The support C in Fig. 2 is pivoted in the bracket B and has its left-hand end M located in a socket N in the bottom of the oil-well D'. When it is desired to remove the 60 oil-well, it is lifted from the support C, which latter is swung out of the way.

In the construction shown in Fig. 1, as well as that shown in Fig. 2, it will be noticed that the oil-well D or D' is supported entirely 65 independent of the other portions of the switch.

Projecting from the back of the switchboard is the supporting-plate O. The bottom of this support is provided with the flanges P, which receive the top of the oil-well D or D'. 70 Mounted upon the support O are the insulators Q, and carried in these insulators are the conductors R. On the lower end of these conductors are the spring-plates S.

Mounted to reciprocate in an opening in the 75 top of the support O is a rod T, on the end of which is a bridge-piece U, formed of conducting material and carrying on its outer ends the spring-contacts V, which are adapted to co-operate with the spring-contacts S on the 80 end of the conductors R. Mounted upon the upper side of the support O is a vertical guide W for the reciprocating rod T.

To make and break contact in the switch from a distance, I make use of the magnets 85 5', which are mounted in a bracket 6 on the front of the switchboard. Within these magnets are the cores 7 8. To these cores are connected a band 9, which passes over a band-wheel 10, mounted on shaft 11, which has its 90 bearings in the bracket 6.

Mounted on the shaft 11 is a crank-arm 12, which is pivotally connected to the bent lever 13. The opposite end of the lever is pivotally connected to the short arm 14 of a bell-crank 15, which is pivoted at 16 at the top of

the support O. The opposite arm 17 of the bell-crank is pivotally connected to a link 18, also pivotally connected at its upper end to the reciprocating rod T.

5 The operation of this portion of the device will be readily understood. When a current is sent through the magnet 5, its core 8 is attracted and the band - wheel 10 and crank-arm 12 are rotated to the right to the position shown in Fig. 1, thereby reciprocating the rod T vertically and causing the bridge-piece U to lap the contacts S of the conductors R. Conversely, when a current is sent through magnet 5 its core 7 is attracted and 10 the band - wheel and crank-arm 12 are rotated to the left to the position shown in Fig. 15 2, thereby reciprocating the rod T vertically and causing the bridge-piece U to break contact with the contacts S of the conductors R.

20 I do not limit myself to the mechanism described for effecting the motion of the vertically-acting bridge-piece U. Other electrical or mechanical devices may be employed.

Having thus described my invention, I 25 claim—

1. In an electric switch, the combination of a switchboard, a bracket-support projecting from said switchboard, switch mechanism carried by said support, an oil-well mounted under said support, and means for supporting the oil-well independently of the support.
2. In an electric switch, the combination of a switchboard, a bracket-support projecting from said switchboard, switch mechanism carried by said support, and an oil-well detachably and independently supported immediately beneath said bracket-support.
3. In an electric switch, the combination of a horizontal plate, switch mechanism carried 40 by said plate, comprising in part switch-contacts and a vertically - reciprocating bridge-piece, an oil-well in which the switch-contacts and bridge-piece are immersed, and means for supporting the oil-well independently of the horizontal plate.
4. In an electric switch, the combination of a horizontal plate, switch mechanism carried thereby, comprising in part switch-contacts and a reciprocating bridge-piece, electromagnetic means for reciprocating the bridge-piece, an oil-well, and means for supporting the oil-well independently of the supporting-plate.
5. An electric switch comprising a switchboard, a horizontal supporting-plate on the 55 rear of the switchboard, electrical contacts depending from said plate, a reciprocating bridge-piece, an oil-well, and means for supporting the oil - well independently of the horizontal plate.
6. An electric switch comprising a switchboard, a horizontally-disposed plate on the rear of the switchboard, switch mechanism involving the employment of a bridge-piece carried by said plate, an oil-well, means on the 65 back of the switchboard for supporting the

oil-well independently of the plate, and means on the front of the switchboard for reciprocating the bridge-piece.

7. An electric switch comprising a switchboard, a horizontal plate on the rear of the switchboard, electrical contacts depending from said plate, a reciprocating bridge-piece, an oil-well immersing said contacts and bridge-piece, means on the front of the switchboard for reciprocating said bridge-piece, comprising a pair of magnets, cores for said magnets, a shaft, a band-wheel on said shaft, a band passing over the wheel and having its ends connected to the cores, a crank-arm on the shaft, and means interposed between said crank-arm and said bridge-piece.

8. In an electric switch, the combination of a switchboard, a bracket-support extending from the back of the switchboard provided with a flanged recess on its under part, an oil-well situated below the support and in such relation that its top will coat with the flanged recess, and means for supporting the oil-well independently of the bracket-support.

9. In an electric switch, the combination of a switchboard, a bracket-support extending from the back of the switchboard provided with a flanged recess on its under part, an oil-well situated below the support and in such relation that its top will coat with the flanged recess, and pivoted means for supporting the oil-well independently of the bracket-support.

10. In an electric switch, the combination of a switchboard, a bracket-support extending from the switchboard, an oil-well situated immediately under the bracket-support, and a pivoted support for the oil-well mounted on the switchboard and detachably connected to the oil-well.

11. In an electric switch, the combination of a switchboard, a bracket-support extending therefrom, an oil-well located immediately under the bracket-support, an arm pivoted to the switchboard and situated at its forward end under the oil-well.

12. In an electric switch, the combination of a switchboard, a bracket-support, projecting from the back of the switchboard, an oil-well located immediately under the bracket-support and provided with a countersunk recess on its bottom, an arm pivoted to the switchboard and provided at its outer end with an upwardly - extending projection which coacts with a recess in the bottom of the oil-well.

13. In an oil-switch, the combination of a switchboard, a bracket, a pivoted arm mounted in said bracket, and an oil-well detachably supported upon the end of said pivoted arm.

In testimony whereof I affix my signature in the presence of two witnesses.

HENRY PRICE BALL.
